UNITED STATES PATENT OFFICE.

JOSEPH GARRICK, OF MICHIGAN CITY, INDIANA.

PROJECTILE FOR CARRYING EXPLOSIVE SHELLS.

SPECIFICATION forming part of Letters Patent No. 300,592, dated June 17, 1884.

Application filed February 26, 1884. (No model.)

To all whom it may concern:

Be it known that I, JOSEPH GARRICK, of Michigan City, in the county of La Porte and State of Indiana, have invented certain new and useful Improvements in Projectiles for Con-
5 cussive Explosive Compounds; and I do hereby declare that the following is a full, clear, and exact description of the invention, which will enable others skilled in the art to which it
10 appertains to make and use the same, reference being had to the accompanying drawings, and to the letters of reference marked thereon, which form part of this specification.

My invention relates to that class of fire-
15 arms—both small arms and ordnance—in which a long secondary projectile is used; and it consists, essentially, in so making the said secondary projectile that, while its base rests against the charge within the gun, its forward
20 end will extend out of the mouth of the same, this forward end being enlarged in diameter and bored longitudinally for the reception of a shell filled with nitro-glycerine or other equivalent explosive. The shell may be either spheri-
25 cal or elongated in form.

Heretofore secondary projectiles have been made with wings or guides that fitted the bore of the gun, having an air chamber or space between said bore and the body of the projectile,
30 which would evidently become filled with gas generated by the ignition of the charge within the gun, which gas became ignited before the departure of the secondary projectile from the bore. This space extending to near the chamber holding the shell filled with nitro-glycerine endangered it to explosion of the same by the close proximity of the flame from the charge. By my invention I avoid all the above-stated
35 dangers.

40 Referring more particularly to the drawings hereto annexed, Figure 1 represents a side view of the invention, partly in section, showing the primary and secondary projectiles in place. Fig. 2 is a longitudinal section of the secondary projectile provided with a spherical shell, and Fig. 3 a side view of the secondary projectile made to receive an elongated shell.

45 In the accompanying drawings, A represents the gun in section, carrying the secondary projectile B, which fits snugly and tightly within the bore of the gun.

C is the charge immediately to the rear of the projectile B, and D is the vent-opening into the chamber just above C.

E is the enlarged front end of the projectile 55 B, provided with the longitudinal chamber F, in which rests snugly the shell G, which may be either spherical or elongated in shape, and to the front end of which is fixed the fulminating-cap H. The projectile B is made of wood 60 or some equivalent light substance, the object being to have it much lighter, bulk for bulk, than the filled shell. The outward extension of the projectile may be varied to form the re-
65 cess of different diameters, and of different con- tour, whereby projectiles or shells of different caliber and shape may be used and projected from the same gun. To do this the tail of the secondary projectile B will be of the same size to fit the same or other guns of like character; 70 but the size of the shell may be varied to suit. While the tail of the projectile B is made to snugly fit the bore of the gun, I prefer that it fit tightly, so that considerable friction may be caused between the tail of the projectile and the 75 bore of the gun, and, indeed, when breech-loaders are used, a tapering pin or wedge may be inserted and driven home to cause such friction. The function of this friction is well-known to
80 those skilled in the art of gunnery.

85 Before the shell is placed in the cylinder of the secondary projectile, I insert a cushion-piece, I, made of rubber or other soft substance having elastic properties. This cushion is pref-
erably made with its center cut out, so that the bearing will be more squarely against or near the periphery of the shell, the object being to secure as little impact as possible between the cylinder and end of the shell, thus lessening the danger of explosion of the nitro-glycerine with-
90 in the shell. Another object of this is that when the cylinders are bored out there remains a central projection on the end wall thereof, which prevents the shell from lodging home. The shell may not, therefore, be lodged in its 95 proper position. The cushion above described obviates this difficulty and objection. In fact, where the shell to be used is of greater weight than would be safe to trust to the strength of wood, a metal cylinder must be substituted. In 100 this case it is absolutely essential that an elastic cushion must be used. A wood cushion in-

terposed between the metal—*i. e.*, the iron of the cylinder and that of the shell—will answer the purpose.

It is evident that metal bands or hoops may be used to strengthen the wooden cylinder of the secondary projectile, with good results. This secondary projectile B may be made in sections, if desirable, which may be keyed together or screw-threaded in the ordinary or any suitable manner. This is done for the purpose of facilitating the transportation of the projectiles, and which may be so formed as to snugly fit in the caisson of the carriage.

The operation of the invention is as follows: 15 The gun having been fired, the projectile B, which tightly fits the bore, is driven out by the force of the explosion; but the shell G, being of greater specific weight and less diameter than the said projectile, and also not fitting 20 the latter so closely as to be held back by friction, will keep up its momentum and velocity long after the projectile B has lost both. The shell G thus gets all the force of the charge without being either in contact with or sufficiently near the same to be exploded by the 25 force of the flame, or of the charge impact, and, because of the nitro-glycerine or equivalent explosive with which it is filled, it will explode when it strikes with very much greater 30 force than the ordinary shell.

Having thus described my invention, what I claim is—

1. The combination, with the barrel A, suitably charged, of the secondary projectile having body tightly fitting the bore thereof down 3 to and in contact with the charge, and constructed with the enlarged head having the chamber F for the reception of a shell, the explosive shell fitting therein having attached to its forward end a fulminating-cap, and an 4 elastic cushion located in the chamber intermediate of the inner end of said shell, substantially as and for the purpose described.

2. The combination, with the secondary projectile constructed with the body B, having the 4 enlarged front end, in which is formed a chamber, of the shell G, filled with nitro-glycerine or other explosive, and an elastic cushion located in said chamber intermediate of the shell, said cushion having its center slightly concave 5 or hollowed out, substantially as and for the purpose described.

In testimony that I claim the foregoing as my own I affix my signature in presence of two witnesses.

JOSEPH GARRICK.
